United States Patent Office.

JOHN H. KEYSER, OF NEW YORK, N. Y.

Design No. 4,816, dated April 18, 1871.

DESIGN FOR A STOVE.

The Schedule referred to in these Letters Patent and making part of the same.

I, JOHN H. KEYSER, of the city and county of New York, in the State of New York, have invented and produced a new and original Design for a Stove, of which the following is a specification, reference being had to the annexed photographic illustration, to which reference is made.

The figure annexed represents a perspective view of the front, top, and one end of the stove design.

The nature of the design consists of two pillars rising from the hearth-plate of the stove, the bases of which are rectangular, terminating above in rounded columns in *alto rilievo*.

Between the latter columns two bee-hives are represented, one on each side of an ornamental figure, on which is formed the words "For coal or wood" partly encircling an ornamental register.

I claim as my invention—

The design for the front of a stove, as represented.
JOHN H. KEYSER.
